UNITED STATES PATENT OFFICE.

AUGUST SUNDH, OF HASTINGS-UPON-HUDSON, NEW YORK.

GATE-HINGE.

1,136,379.

Specification of Letters Patent. Patented Apr. 20, 1915.

Application filed December 10, 1914. Serial No. 376,402.

To all whom it may concern:

Be it known that I, AUGUST SUNDH, a citizen of the United States, residing in Hastings-upon-Hudson, in the county of 5 Westchester and State of New York, have invented a new and useful Improvement in Gate-Hinges, of which the following is a specification.

My invention relates to improvements in 10 gate hinging mechanism and more particularly to that type known as self closing.

The various objects of the invention will be fully stated hereinafter in connection with the detailed description, but briefly 15 stated they are as follows, to wit,

The provision of a gate hinging mechanism which is self closing from both directions; a hinging mechanism that is easy to assemble; a hinging mechanism which will 20 be well lubricated at all times; and a hinging mechanism which will be well protected from the elements, and from foreign substances getting to the inside and wearing out the bearings.

25 Referring to the drawings, which illustrate my invention, and which like parts are represented by like reference characters, Figure 1 is an elevation view partly in section of one part of my apparatus in place 30 on a gate and gate post; Fig. 2 is a plan view of part of the apparatus shown in Fig. 1.

Referring to Fig. 1, I have shown part of 35 my apparatus applied to a gate, 1, and gate post, 2. The hinge is made up of two cylindrical cups, 3 and 4, which fit over each other in a manner hereinafter more fully pointed out. Extending from the bottom of the cup, 4, is an arm, 5, which is secured 40 to the gate post 2, in any desired manner, but here shown as having its end, 6, concave, to conform to the shape of the gate post. Another part or clamp, 7, the end of which 45 is concave also, is provided, which fits over the opposite side of the gate post from the end, 6, of the arm, 5. The parts, 6 and 7, are then held fast to each other, and the gate post, by means of screw bolts, 8, of which there are two. I have merely shown this 50 method of attaching the hinge to the gate post for the purpose of illustration. Set securely into the arm, 5, is a spindle, 9, extending upwardly to near the top of the cup. Formed in the inside of the cup, 4, 55 at the bottom, and surrounding the spindle, 9, is a boss, 10, carrying ball bearings, 11.

Mounted upon the ball bearings is a plate 12^a which is practically of the same diameter as the boss, 10. The upper cup, 3, when in place is inverted and fits over the lower cup, 4. This cup, 3, is formed on its inside with an extension cylinder, 12, concentric with the inner surface of the cup, and of a diameter slightly less than that of the plate 12^a. The bore of this cylinder is enough larger than the diameter of the spindle, 9, to permit of roller bearings, 13, being placed between the spindle and the bore of the cylinder. The cylinder, 12^a, is of such a length that when its lower end 65 rests on the plate, 12, there will be a slight clearance between the top of the cup 4 and the inside of the bottom of the cup, 3. The cup, 3, is further provided at the left of the part, 12, (Fig. 1) with a downwardly 70 extending projection, 14. This projection rests on the top of the cup 4 and the inside of the bottom of the cup, 3. The cup, 3, is further provided at the left of the part, 12, (Fig. 1) with a downwardly 75 extending projection, 14. This projection extends downwardly nearly to the bottom of the inside of the cup, 4; the clearance between the bottom of the cup and the end of the projection being merely a matter of 80 choice, except that the part, 14, must extend downwardly at least to the top of the plate, 12^a, and preferably a little below it. Formed on the inside of the cup, 4, at the left of projection, 14, in Fig. 1, and extending vertically up the side of the cup 85 is a rib, 15. Surrounding loosely the part, 12 and resting on the plate 12^a, is a coil spring, 16, the ends of which extend to the left as viewed in Fig. 1, straddling the projection, 14, and the projection, 15. This spring has to be forced into place as it is put under tension when made to straddle the projections 14 and 15. This tension on it will keep the parts 14 and 15 abreast 90 of each other when the hinge is not being operated. Extending from and pivoted to a boss, 16, formed on the outside of the cup, 3, abreast of the bore of the cylinder, 12, is an arm, 18, which is fastened to the gate. 100 I have shown this arm bent to conform to the shape of the gate and held in place to the gate by two screws, 19, 19, but it is to be understood that the arm may be secured to the gate by any convenient means. 105

To provide lubricant to the hinges, I fill the cup 4 partially full of oil or some other lubricant, L. It will thus be seen that the parts will always be well lubricated.

With a hinge arranged as I have shown 110 mine, it will be seen that friction is reduced to a minimum, as not only are the parts

immersed in oil, insuring perfect lubrication, but I have provided ball and roller bearings to take care of both end and lateral thrust. Owing to the relative lengths of 5 the parts 12 and 4, the part 12 will rest on the plate 12^a before the part 4 engages the cup 3. This means that whatever downward thrust there is on the hinge will be taken up by the balls 11. When the part 10 3 is swung around in one direction or the other to open the gate, the spring 16 will be placed under additional tension by the action of the parts 14 and 15, which tension will center the hinge when the gate is released. As 15 before stated the spring being always under some tension will tend to keep the parts centered when the hinge is not being operated.

Having thus described my invention, I desire not to be limited to the precise construction herein disclosed, it being understood that persons skilled in the art may make various changes in the details of construction and arrangements of parts as herein shown, without departing from the spirit 25 and scope of the invention.

What I claim and desire to have protected by Letters Patent of the United States is:—

1. In a hinge, a stationary member, a central spindle, a revolute member having a 30 socket extending over said spindle and guided thereby, a center position for said revolute member, a stop in the stationary member, an extension on the revolute member, a torsional spring surrounding the 35 spindle and the socket and guided thereby, one end engaging on one side of the stop and the other end engaging on the other side of the stop in the stationary member, the extension of the revolute member being 40 interposed between the ends of said spring, thereby holding the revolute member in central position.

2. In a hinge, a stationary member, another member adapted for manual operation 45 in one direction or the other from a central position, a central spindle supported by the stationary member, the manually operable member having a socket extending over said spindle and guide thereby, a stop in the 50 stationary member, an extension on the manually operable member, a torsional spring surrounding the spindle and the socket and guided thereby, the ends of the spring engaging the stop in the stationary 55 member and held under torsional tension by said stop, the extension of the manually operable member being interposed between the ends of said torsional spring and held in a central position thereby, said extension

adapted to wind up the spring when the 60 manually operable member is operated to one side or the other from a center.

3. In a hinge, a stationary member, another member adapted for manual operation in one direction or the other from a central 65 position, a central spindle for said members, sockets in the said members for holding and guiding the members, a torsional spring surrounding the said spindle with its two ends extending out and engaging with a stop in 70 the stationary member and held under torsional strain by said stop, an extension in the manually operable member interposed between the ends of said torsional spring and held in a central position thereby, said 75 extension adapted to operate the spring to cause same to store up tensional spring power by the operation of the manually operable member, this tension adapted to force the manually operable member back 80 to a central position.

4. A hinge, comprising stationary and revolute members, the stationary member constructed to hold a lubricant, and mechanism consisting of a central spindle for holding and guiding said members relative to each other, a torsional spring surrounding said spindle, means always to hold said spring under tension and to increase said tension upon manual operation of the revolute member, roller bearings for the spindle, the revolute member having downwardly extending walls freely fitted to clear the walls of the stationary member. 85

5. A hinge, comprising stationary and 90 revolute members, the stationary member constructed to hold a lubricant, coöperating mechanism for said members, said mechanism consisting of a center spindle with antifriction bearings, a torsional spring, 100 means to hold said spring under torsional strain, means to obtain an increased torsional spring tension by a manual operation of the revolute member, said revolute member having walls extending downward 105 and freely fitted to clear the walls of the stationary member, a pivoted lever connected to said revolute member and adapted to suspend a load and also adapted to transmit a manual operation to the revolute member. 110

In testimony whereof, I have signed my name to this specification in the presence of two subscribing witnesses.

AUGUST SUNDH.
